CLAIM

The ornamental design for a dispenser for cleanser compositions, as shown and described.

DESCRIPTION

FIG. 1 is a front and side perspective view of the dispenser for cleanser compositions showing my new design;
 FIG. 2 is a front plan view, the rear view being a mirror image of the front view;
 FIG. 3 is a left plan view;
 FIG. 4 is a right plan view;
 FIG. 5 is a top plan view thereof; and,
 FIG. 6 is a bottom plan view thereof.
